UNITED STATES PATENT OFFICE

ELMER G. GARTIN, OF CLAREMONT, NEW HAMPSHIRE, ASSIGNOR TO SULLIVAN MACHINERY COMPANY, A CORPORATION OF MASSACHUSETTS

ROCK DRILL FEEDING DEVICE

Application filed August 18, 1930. Serial No. 475,946.

My invention relates to rock drill feeding devices, and more particularly to feeding devices of the kind used in stoping drills. An object of my invention is to provide an improved feeding device for a stoping drill. Another object is to provide an improved feeding device for a stoping drill in which loss of lubricant can be avoided while at the same time insuring the proper notification of the drill runner that a change in drill steels is necessary.

The usual stoping drill feed has a port known as a tell-tale, which is uncovered by the feed piston just before the feed cylinder and feed piston reach their relative position of maximum extension, in other words, just before the limit of feed is reached. This is very important as it advises the runner that it is necessary to collapse the feed and change the steel. At the same time it is a source of difficulty in view of the fact that it seriously interferes with proper lubrication of the feed and results in a considerable loss and waste of lubricant. It is customary to put a substantial quantity of grease or the like into the feed cylinder above the feed piston in "direct type" feeds, and if it were not for the fact that this lubricant is blown out very promptly through the tell-tale, a small quantity would suffice for lubrication for quite a period. When it is blown out the packings tend to dry and sticking occurs. It would therefore be desirable to eliminate the tell-tale if possible or at least to eliminate its disadvantageous effect on the lubrication of the feed. It is a specific object of my invention to accomplish this desired result by retaining the function of the tell-tale, namely of discharging a jet of air as the limit of feed is approached, while at the same time preventing the flowing out of the lubricant from the feed cylinder. Other objects and advantages of my invention will hereinafter subsequently appear.

In the accompanying drawings, in which for purposes of illustration three forms of the invention are shown,

Fig. 1 is a central vertical section through a stoper feed mechanism in which one species of my invention is embodied;

Fig. 2 is a corresponding view showing the parts in a different relative position;

Fig. 3 is a section on the line 3—3 of Fig. 1;

Fig. 4 is a fragmentary view on a similar section to that of Fig. 1 showing a second species of the invention; and

Fig. 5 is a central vertical section showing a third species of the invention.

Referring to the drawings, 1 represents the block which intervenes between a percussive motor, not shown, and the feeding mechanism, which is generally designated 2. Within the head block is a throttle valve 3 which controls the supply of air to the feeding mechanism. The feeding mechanism 2 comprises a feed cylinder 5, a bushing or sleeve 6, which cooperates with parts later described to retain the feed in collapsed position, and a collar 7 which is secured by side rods or other bolts to the head block or the drilling motor for the purpose of maintaining the feed and other parts in assembled relation. The feed cylinder has at its lower end a head 8 through which a bore 9 is formed, and the lower end of the feed cylinder is surrounded by a clamp 10, through which and the head 8, a bolt 11 passes. The feed further includes within the feed cylinder 5, a feed piston 13 having a piston rod 14 formed of a tubular member 15 attached to end sleeves 16. The lower sleeve carries a point 17 threaded into its lower end, and the upper end of the upper sleeve is reduced as at 19 to extend through the feed piston proper, which comprises a plate 20, an intermediate member 21 and a follower member 22, there being cup leathers 23 clamped between the member 21 and the members 20 and 22. The upper end of the reduced portion of piston rod 14 is threaded and has a nut member 25 screwed thereon and retaining in position a spring 26, which is adapted to enter a bore 27 in the sleeve 6 and yieldingly retain the feed in collapsed position. The reduced extension 19 is provided with a longitudinally extending bore 29 having an upper portion 30 of larger diameter. Within this bore a valve 31 is reciprocable; the valve comprising a lower guide stem 32 in the bore 29, an intermediate reduced portion 33, and a head 34.

adapted to engage a valve seat 35 at the junction of the enlarged bore 30 and the small bore 29. A spring 36 engages the top of the valve and a stop member 37 mounted transversely of the bore 30, and normally maintains the valve 34 seated upon the seat 35. A passage 38 extends from a point below the valve seat 35 laterally and then downwardly into the interior of the upper sleeve member 16 of the piston rod, and ports open laterally through the walls of the piston rod as at 40, these ports being arranged in such position that they pass below the cylinder head 8 just as the limit of feed is approached. The valve stem 32 projects into a transverse opening 41 formed through the piston rod 14; and a transversely extending pin 42 lies within this opening and is attached at its opposite ends to a ring or annular member 43. This member 43 is engageable with the upper surface of the lower cylinder head 8 just before the limit of feed is reached, and thus raises the transverse rod or pin 42 and, accordingly, the valve 34 and thereby permits the flow of fluid from the feed cylinder past the valve 34 through the passage 38 and through the interior of the piston rod out through the passages 40 which at the same time become exposed just below the lower head 8 of the feed cylinder.

From what has been said it will be readily understood that when the feed is nearly completed, the ports 40 become exposed below the cylinder head 8 and substantially at the same time the ring 43 engages the upper surface of the cylinder head 8 and, as the cylinder head continues to approach the piston, the plunger 32 is raised unseating the valve and permitting air to flow from the axial portion of the feed cylinder through a passage spaced from and above the cup leathers, through a series of passages, and finally out of the ports 40, to serve as a tell-tale. There is no loss of any substantial amount of lubricant, however, because the lubricant adheres to the cylinder walls and cup leathers, whereas the air which blows outward to notify the drill runner that the feed is fully out comes from the center or axial portion of the cylinder and not from a point adjacent the cylinder wall.

In the species of the invention shown in Fig. 4 a valve corresponding in function to the valve 32 is employed, but it is differently arranged in the piston head and is directly engaged with the lower cylinder head near the end of the feed. In this construction the head block 1, the clamp 7, feed cylinder 5, and sleeve 6 may be the same as in the construction of Fig. 1. The piston rod is of plural part construction and comprises a tubular member 15' attached to a sleeve 16'. The sleeve 16' has an enlargement 45 of substantially the full cross sectional area of the cylinder, and has above the enlargement, a

reduced portion 46, surrounded by members 20, 21, 22 and cup leathers 23, of substantially the same construction as the correspondingly numbered parts of Fig. 1. A nut 25 cooperates with a threaded portion at the upper end of the portion 46 to hold the parts together and position a spring ring 26. A passage 48 extends axially through the extension 46 from the upper end of the latter to a point within the enlargement 45. A valve chamber 49 is formed below the plate 20 in the enlargement 45 and a valve 50 is mounted in the chamber. A sleeve 51 provides a seat 52 for the head 53 of the valve and a guide 54 for the stem 55 of the valve. The valve is reduced at 56 just below its head. Passages 57 and 58 respectively connect the space above the valve head 53 with the passage 48 and the space below the valve head 53 with the hollow bore of the piston rod 15. The stem 55 of the valve projects below the bottom of the enlargement 45 when the valve is seated and is adapted to engage the lower head (not shown) of the feed cylinder just before the end of the forward feed is reached. The piston rod is provided with passages 40' which are located to cause them to be uncovered below the lower head of the feed cylinder just as the valve stem 55 engages the latter.

The mode of operation of this form of the invention will also be apparent. It may be summarized by stating that during all but the last portions of the forward feed the head 53 of valve 50 prevents communication between the bore of the feed cylinder above the feed piston and the space within the piston rod 15'. When, however, the enlargement 45 and the lower head of the feed cylinder are close enough together, the valve stem 55 is engaged by this cylinder head and the valve 50 permits pressure fluid to pass from the working space in the feed cylinder through passages 48, 57, and 58 and through ports 40', to signal to the drill runner the approach to the limit of feed. The air which serves as a "tell-tale", being taken from the axial part of the cylinder bore and from a point substantially spaced from the cup leathers and cylinder walls, carries with it very little lubricant and therefore serves its signalling purpose while lubricant is conserved.

Fig. 5 discloses a third species of my invention. In this form the piston proper has the valve incorporated in it rather than carrying a separate valve element. The usual head block 1 provided with a suitably controlled passage 4 for the feeding pressure fluid has secured thereto by a clamp 7 a feed cylinder 5 and also a sleeve member 6. A feed piston 60 is mounted on the upper end of a piston rod generally designated 61. The latter comprises a tubular member 62 attached to a sleeve 63 and is hollow and traversed by "tell-tale" ports 64 which are positioned to cause their exposure below the

lower head of the feed cylinder just before the limit of forward feed is attained. The rod structure includes a shoulder 65 and a reduced portion 66, the latter having at its upper end a threaded portion 67 supporting a nut 68 which carries a spring 69 adapted to cooperate with the sleeve member 6 to keep the feed in collapsed position during transport. Slidable on the reduced portion 66 is the piston structure proper, and this comprises a lower plate 72 engaging the shoulder 65, an intermediate member 73 and a top member 74, cup washers being mounted between the intermediate member 73 and plate 72 and top member 74 respectively. A spring 76 abutting against the nut 68 and the top member 74 forces the component parts of the piston together and maintains them in their lowest position. A passage 75 extends downwardly through the reduced portion of the piston and a passage 76 extends upwardly almost to the passage 75 from the interior of the piston rod. These passages 75 and 76 have portions which open laterally through the cylindrical wall of the reduced portion 66. The intermediate member 73 has an internal groove 77, normally communicating only with the passage 76 but adapted on relative longitudinal movement between the piston and its rod to connect the passages 75 and 76 and permit flow of pressure fluid from the interior of the feed cylinder through passage 75, groove 77, passage 76 and ports 64 to the atmosphere.

The operation of this form of the invention will be obvious from the description given. During the major part of feeding movement the piston will engage the shoulder 65 and no air will reach the ports 64. When the feed piston contacts with the lower head of the feed cylinder, relative movement between the piston and piston rod will take place and the groove 77 will connect the passages 75 and 76 and air will flow from the feed cylinder to the port 64 and notify the operator that the limit of feed is reached. Obviously, however, no material loss of lubricant will occur, due to the locus of the inlet to the passage 75.

From the foregoing description of several of the different forms which my invention may assume in practice, it will be evident that I have provided an improved feeding mechanism which retains the familiar signal of the usual "tell-tale", but which prevents the very rapid loss of lubricant which has been found to attend upon the use of the "tell-tale" port as usually arranged. Moreover, my improved arrangements are simple, rugged, not easily damaged, and require no attention not ordinarily accorded the drilling device by the runner.

While there are in this application specifically described three forms which the invention may assume in practice, it will be

understood that these forms are shown for purposes of illustration and that the invention may be modified and embodied in various other forms without departing from its spirit or the scope of the appended claims.

What I claim as new and desire to secure by Letters Patent is:

1. In a drilling mechanism, relatively movable feed cylinder and piston elements, the latter having a piston rod, and means for indicating the attainment of maximum extension between the cylinder and piston including a tell-tale port in the piston and means for supplying air thereto only at about the limit of feed.

2. In a drilling mechanism, a feed cylinder, a feed piston reciprocable therein, and means for indicating the attainment of maximum relative movement therebetween including a tell-tale port and means for conducting fluid thereto from the cylinder bore communicating with the bore of said cylinder only adjacent the axis thereof.

3. In a drilling mechanism, a feed cylinder, a feed piston in said cylinder, a tell-tale port, and means for controlling fluid flow thereto including a valve supported by said piston.

4. In a drilling mechanism, a feed cylinder, a feed piston therein having a piston rod, a tell-tale port, and means controlling flow of fluid through said port including a valve movable relative to said piston rod.

5. In a drilling mechanism, a feed cylinder, a feed piston therein having a piston rod, a tell-tale port, and means controlling flow of fluid through said tell-tale port including a valve within said piston movable relative to said piston rod.

6. In a drilling mechanism, a feed cylinder, a feed piston therein having a piston rod, a tell-tale port, and means for controlling flow of fluid through said tell-tale port including a valve movable relative to said piston and piston rod.

7. In a drilling mechanism, a feed cylinder, a feed piston therein having a piston rod, a tell-tale port, and means for controlling flow of fluid through said tell-tale port including a valve coaxial with said piston rod.

8. In a drilling mechanism, a feed cylinder, a feed piston therein having a piston rod, a tell-tale port, and means for controlling flow of fluid through said port including a valve at the axis of said rod.

9. In a drilling mechanism, a feed cylinder, a feed piston therein having a piston rod, a tell-tale port, and means for controlling flow of fluid through said port including a sleeve valve coaxial with said piston rod.

10. In a drilling mechanism, a feed cylinder, a feed piston therein having a piston rod, a tell-tale port, and means for controlling flow of fluid through said port including a valve parallel to the axis of said piston rod.

11. In a drilling mechanism, a feed cylinder, a feed piston therein having a piston rod, a tell-tale port, and means for controlling flow of fluid through said port including a valve operated by relative movement between said piston and cylinder.
12. In a drilling mechanism, a feed cylinder, a feed piston therein having a piston rod, a tell-tale port, and means for controlling flow of fluid through said port including a valve operated by relative movement between said piston and piston rod.
13. In a feeding mechanism, a feed cylinder, a feed piston therein having a piston rod, said piston rod having a tell-tale port therein, and means for controlling flow of fluid to said port including a passage opening into the cylinder bore adjacent the axis of the latter, and a valve reciprocable longitudinally of the cylinder for controlling flow of fluid in said passage.
14. In a feeding mechanism, a feed cylinder, a feed piston therein having a piston rod, said piston rod having a tell-tale port therein, and means for controlling flow of fluid to said port including a passage opening into the cylinder bore adjacent the axis of the latter, and a valve reciprocable longitudinally of the cylinder for controlling flow of fluid in said passage, said valve having a stem and said cylinder having associated therewith means engageable by said stem as the limit of feed is approached.
15. In a feeding mechanism, a feed cylinder, a feed piston therein having a piston rod, said piston rod having a tell-tale port therein, and means for controlling flow of fluid to said port including a passage opening into the cylinder bore adjacent the axis of the latter, and a valve reciprocable longitudinally of the cylinder for controlling flow of fluid in said passage, said cylinder and valve having elements associated therewith cooperating to effect opening of said valve when the limit of feed is approached.

In testimony whereof I affix my signature.
ELMER G. GARTIN.
